FIRING MECHANISM

James W. Channell, San Marino, Calif., assignor
to the United States of America as represented
by the Secretary of the Navy.

Application March 15, 1943, Serial No. 479,271

12 Claims. (Cl. 102—70.2)

1

This invention relates to firing mechanisms, and more particularly to impact firing mechanisms for bombs.

It is an object of this invention to provide a firing mechanism for a bomb wherein the booster charge and the detonator are resiliently held apart, and wherein the booster is moved against the resilient means upon impact of the bomb to receive the detonator in a recess therein provided.

A further object of the invention is to provide in a firing mechanism of the character described, latching means to hold the booster in its forward position after impact of the bomb.

Another object of the invention is to provide a firing mechanism of the character described with a mercury switch in which the contacts of the switch are in one chamber and the mercury in a separate chamber, with means to transfer the mercury from the one chamber to the contact chamber by the movement of the booster upon impact of the bomb.

Still another object of this invention is to provide a firing mechanism of the character described with means for a time delay between the impact of the bomb and the firing thereof.

Yet a further object of this invention is to provide a firing mechanism of the character described with a battery cell normally inactive, but adapted to be activated upon impact of the bomb.

Yet another object of this invention is to provide a firing mechanism of the character with a safety release to prevent accidental movement of the booster.

Still another object of this invention is to provide a highly improved, compact and rugged firing mechanism of the character described which shall be relatively inexpensive to manufacture, extremely safe in handling, yet positive and efficient to a high degree in use.

Other objects of this invention will in part be obvious and in part hereinafter pointed out.

This invention accordingly consists in the features of construction, combinations of elements, and arrangements of parts which shall be exemplified in the construction hereinafter described, and of which the scope of application will be indicated in the following claims.

In the accompanying drawings in which several embodiments of this invention are illustrated:

Fig. 1 is a cross sectional view of a firing mechanism embodying one form of the invention.

Fig. 2 is a cross sectional view of a modified form of mercury switch.

Fig. 3 is a cross sectional view taken along the line 3—3 of Fig. 2.

2

Fig. 4 is a view of the nose cap switch and battery section, partly in elevation and partly in cross section.

Fig. 5 is a plan view of the nose cap switch.

Fig. 6 is a schematic wiring diagram of one form of the firing circuit.

Fig. 7 is a view of the battery section, partly in elevation and partly in cross section.

Fig. 8 is an elevational view of the firing mechanism positioned in a projectile.

Fig. 9 is a schematic wiring diagram of a second firing circuit.

Referring now in detail to Figs. 1 and 8 of the drawings, 10 designates a firing mechanism embodying one form of the present invention. The firing mechanism 10 is supported in a cylindrical recess 11 of a projectile 12, and fixed to the nose thereof as by threads 13. A safety release cable 14 of the firing mechanism passes through the projectile, as by opening 15, and extends beyond the tail surfaces.

Firing mechanism 10 comprises a supporting shell or casing 16 threaded to the nose cap or striking point 17. Fitted within the nose portion 18 of shell 16 is a battery section 19 consisting of a threaded tube 19 and a dry cell 20. A washer 21 of insulating material is placed between the battery and nose cap 17.

Threaded to the tube 19 is a mercury switch section 22, comprising a member 23 made of insulating material. Member 23 is formed with two cylindrical recesses 24, hereinafter called the immediate chambers, sealed by screws 25. Each recess is provided with a pair of spaced contacts 26 (Fig. 6). Member 23 is further formed with a third cylindrical recess 27, filled with mercury 27a, and hereinafter called the reservoir. A plug 28 is threaded into the reservoir. Interconnecting the reservoir and the two immediate chambers 24, are two passageways 29, each passageway being provided with a small spring valve 30 (Fig. 2).

Means is provided to pump the mercury from the reservoir through the passageways into the two immediate chambers.

To this end, there is provided a plunger 31, one end of which passes through the plug 28 into the reservoir. Fixed to the end of the plunger by means of a nut 32 and steel washer 33, is a leather washer 34. Plunger 31 is slidably received within a tubular member 35 threaded to the member 23. A light coil spring 36 about plunger 31 tends to hold the plunger against movement in the forward direction. A second coil spring 37 abuts a nut 38 threaded to the end of the plunger and the forward portion of an external plunger 39 slide-

bly received within tubular member 35. The external plunger 39 is provided with a large collar 40 fixed to its end and adapted to hold a detonator 41.

Forward motion of the plunger 31 will pump the mercury through the passageways 29 into the immediate chambers. The spring valves 30 will open due to the increased pressure created by the plunger.

In the rear portion of supporting shell 16 is a booster 42, comprising two concentric tubular members 43 and 44, and provided with end plates 45, formed with openings for the tubular member 43. The space between the two tubular members is filled with an explosive charge 46. Booster 42 is adapted to slide forward within shell 16, against the action of a coil spring 47, upon impact of the projectile, to place the detonator within the recess formed by the tubular member 43. Safety release 14, abutting end plate 48 of shell 16, normally holds the booster against any forward movement.

Means is provided to hold booster 42 in its forward position after impact of the projectile.

To this end there are provided two spring latches 49 fixed to the external surface of tube 16, the latches passing through the tube to rest against the surface of tubular member 44. The latches will catch behind end plate 45 when booster 42 moves into its forward position.

In operation, the projectile is dropped after pulling out the safety release cable 14 to permit the potential forward movement of booster 42. Upon impact of the projectile 12 with its target, booster 42 will slide forward, due to its inertia, in supporting shell 16, against the action of spring 47. The detonator 41 passes within tubular member 43 of the booster. The forward end plate 45 will abut the collar 40, to move the external plunger 39 forward. The forward motion of the external plunger will compress spring 37. The latches 49 will hold the booster 42 in its forward position.

Compressed spring 37 will move the plunger 31 forward against the action of the weaker spring 36, to pump the mercury from the reservoir 27 into the immediate chambers 24, opening the valves 30 in the passageways 29. The contacts of the immediate chambers will thus be bridged by the mercury to complete the firing circuit as shown in Fig. 6, to fire the detonator. The detonator in turn will set off the explosive charge 46 of the booster which in turn will explode the charge of the projectile.

It is evident from the above description and from the wiring diagram as shown by Fig. 6, that the firing mechanism could be constructed with only one immediate chamber 24, instead of the two as disclosed. By using two immediate chambers and placing the contacts in each side of the line of the detonator, added safety is obtained in the handling of the projectile. The use of only one immediate chamber would necessitate connecting one side of the detonator directly to the battery cell. The possibility of the battery cell grounding against the supporting shell and completing the firing circuit for the detonator is thus avoided.

Referring to Fig. 7 of the drawings, a different type of battery cell is disclosed to energize the firing circuit of the detonator 41.

Fitted into the nose portion of supporting shell 16 is a shell 50 to which member 23 is threaded. Fixed within shell 50 is a recessed member 51. Fitted within the recess of member 51 is a casing

52 of insulating material. Within casing 52 is a battery cell 53, normally inactive, enclosed in a glass envelope 54. Enclosing the envelope 54 and its battery cell is a second glass envelope 55 filled with an activating fluid, not shown, for the battery cell. Both glass envelopes are formed with pointed ends which pass through the casing 52.

Means is now provided to break the pointed ends of both glass envelopes to permit the activating fluid to come in contact with the battery cell.

To this end shell 16 is now provided with a nose cap 56 having a removable safety pin 57. The internal end of safety pin supports a heavy metal washer 58. The pointed ends of the glass envelopes are received within the washer. Before use, the safety pin 57 is withdrawn, leaving the washer supported by the tips of the glass envelopes. Upon impact of the projectile, this washer will slide sideways breaking the ends of the glass envelopes to bring the activating fluid in contact with the battery cell.

Referring to Figs. 2, 3, 4, 5 and 9 in which a second embodiment of the present invention is disclosed, means is provided to delay the firing of the detonator after impact of the projectile.

The switch section 22 is now provided with two immediate chambers 24, a reservoir 27 filled with mercury, and a fourth recess 60, hereinafter called the delay chamber. The delay chamber is provided with a pair of spaced contacts 61. Interconnecting the delay chamber and one of the immediate chambers is a passageway 62 for the mercury (Fig. 9).

Shell 16 is provided with a nose cap 63 having an indexing pin 64. The indexing pin actuates the switch member 65, the schematic drawing of which is shown in Fig. 9.

In operation, the indexing pin is first set to the type of firing desired. If contact firing is desired, the pin is set on "C" of the nose cap 63. The firing of the detonator and booster will be the same as hereinabove described.

Should delay firing of the detonator be desired, the indexing pin is set on "D" of the nose cap. Upon impact of the projectile, the booster will move forward to charge the plunger spring 37. The mercury is then pumped into the immediate chambers 24 of the switch section. Due to the setting of switch member 65 (Fig. 9), the detonator will not be fired. The mercury, after filling the immediate chambers, will flow through the passageway 62 to run into the delay chamber 60. When the contacts 61 of the delay chamber are bridged by the mercury, the firing circuit for the detonator 41 is completed (Fig. 9) to set off the projectile.

The time delay in setting off the projectile may be varied according to need, by proper design of the size of the immediate chambers, the diameter and length of the passageway interconnecting the immediate chamber and the delay chamber and by properly positioning the contacts within the delay chamber with respect to the interconnecting passageway and/or the bottom of the delay chamber.

It will thus be seen that there is provided a device in which the several objects of this invention are achieved and which is well adapted to meet the conditions of practical use.

As various possible embodiments might be made of the above invention and as various changes might be made in the embodiments above set forth, it is to be understood that all matter herein set forth, or shown in the accompanying draw-

ings, is to be interpreted as illustrative and not in a limiting sense.

Having thus described my invention, I claim as new and desire to secure by Letters Patent:

1. In a bomb firing mechanism, a shell adapted to be embedded in a bomb enclosing a switching device and an explosive device, resilient means normally holding said devices apart, the said explosive device being slideable forward by the force of its momentum upon impact of the bomb into position to operate said switching device, said switching device comprising a block of insulating material, two pair of spaced contacts in two normally empty chambers in said block, a quantity of mercury adjoining said chambers, a passageway leading from the mercury to said chambers and spring pressed valves normally closing said passageways, means engaging the mercury and movable under the control of said explosive device as it moves forward to cause the mercury to force said valves open and to flow through said passageways to bridge said contacts, and an energizing circuit for firing said explosive device controlled by said switching device.

2. In a bomb firing mechanism, a shell adapted to be embedded in a bomb enclosing a switching device and an explosive device, resilient means normally holding said devices apart, one of said devices being slideable towards the other by the force of its momentum upon impact of the bomb into position to cause the actuation of said switching device, said switching device comprising a block of insulating material having three chambers with a passageway there between together with stoppers normally closing said passageways, two of said chambers being provided with two pair of spaced contacts and the other of said chambers enclosing a conducting fluid, a plunger engaging said fluid and extending through said block into position to be engaged by said explosive device upon impact of the bomb whereby said fluid is caused to displace said stoppers and to flow through said passageways to bridge said contacts, and an energizing circuit for firing said explosive device closed by the bridging of said contacts.

3. In a bomb firing mechanism, a shell adapted to be embedded in a bomb enclosing a switching device and an explosive device, resilient means normally holding said devices apart, one of said devices being slideable towards the other by the force of its momentum upon impact of the bomb into position to cause the actuation of said switching device, said switching device comprising a block of insulating material having four chambers, the first of which encloses a conducting fluid, the second and third of which encloses two pair of spaced contacts and are connected with said first chamber by a normally closed passageway and the fourth of which encloses a pair of spaced contacts and is connected with said third chamber by an open passageway, displaceable valve means initially closing the first mentioned passageway, a plunger extending from within said first chamber through a wall of said block to a position at which the plunger may be pushed inwardly by said explosive device upon impact of the bomb to force the said fluid from said first chamber into said second and third chambers and from said third chamber into said fourth chamber, and an energizing circuit including said pairs of contacts for firing said explosive device.

4. Contact firing mechanism comprising a casing, an insulating block, a plunger, a detonator and a booster aligned in serial order in said

casing, said block having three chambers with mutually connecting passageway therebetween, two of said chambers having two pairs of spaced contacts and the third enclosing a conducting fluid, said plunger extending rearwardly from within the third chamber, resilient means to hold said booster normally apart from said detonator while permitting forward displacement thereof by the force of inertia into a position to be fired by said detonator, latching means to hold said booster against counter movement, resilient means to hold said detonator apart from said plunger while permitting forward movement thereof towards said plunger when said detonator is engaged by said booster and said booster is approaching its fully displaced position, resilient means to prevent said plunger from normally exerting pressure on said conducting fluid while permitting forward movement of the plunger upon reactive expansion of the resilient detonator holding means to cause said conducting fluid to flow through said passageways to bridge said contacts, and an energizing circuit for firing said detonator including said contacts.

5. A bomb firing mechanism according to claim 3, provided with a switch to exclude at will one of said pairs of contacts from said energizing circuit.

6. Electrical activating means for bomb firing mechanism comprising a two-compartment frangible container, each of the compartments being tipped and thereby sealed, one of the tips extending inside of the other tip, an initially inert cell in one compartment, an activating fluid for the cell in the other compartment, and means for shearing the compartment tips thus to break the seal between the compartments.

7. Electrical activating means for bomb firing mechanism comprising a two-compartment frangible container, said compartments having telescoped sealing tips, an initially inert cell in one compartment, an activating fluid for the cell in the other compartment, and a weight movable transversely of the container to shear both tips and thus break the seal between the compartments.

8. Electrical activating means for bomb firing mechanism comprising a two-compartment frangible container, said compartments having telescoped sealing tips, an initially inert cell in one compartment, an activating fluid for the cell in the other compartment, and a radially movable shearing washer hung on the outermost tip.

9. Firing mechanism comprising a casing, an electrical circuit embodied in the casing, including a source of current and at least one pair of contacts, a reservoir containing a volume of conducting fluid, said reservoir having a passageway communicating with the contacts, a two-part plunger of which one part is spaced from the other part and is displaceable in the reservoir for extruding the fluid to bridge the contacts, a detonator carried by the other part of the plunger, said detonator being connected across the circuit, and a booster spaced from the detonator, being movable into proximity therewith and then progressively to close and displace the two-part plunger.

10. Firing mechanism comprising a casing, an electrical circuit embodied in the casing, including a source of current and at least one pair of contacts, a reservoir containing a volume of conducting fluid, said reservoir having a passageway communicating with the contacts, a two-part plunger of which one part is spaced from

the other part and is displaceable in the reservoir for extruding the fluid to bridge the contacts, a detonator, abuttable means by which the detonator is attached to the other part of the plunger, said detonator being connected across the circuit, and a booster spaced from the detonator, being movable into abutment with the abuttable means, thereupon to progressively close and displace the two-part plunger.

11. Firing mechanism for bombs and the like, comprising fluid contact-making means, an electrical circuit having terminals bridgeable by displacement of and contact with said fluid means, a booster spaced from the contact-making means but movable toward it, a two-part plunger of which one part is spaced from the other part and is adapted to pump the fluid means, a detonator carried by the other plunger part which is engageable by the booster, said detonator being connected across the circuit, and tension means exercising different degrees of tension on the respective parts of the two-part plunger, therefore enabling the plunger parts to yield progressively after said other plunger part is picked up during the movement of the booster.

12. Contact firing mechanism comprising a casing, a battery, a switch for a firing circuit embracing the battery, said switch including open contacts, an entrapped volume of contact-bridging fluid and a plunger to extrude it from its entrapment, a detonator and a booster movable from an unarmed position by the force of

inertia into an armed position to be fired by said detonator, and a two-part two-tension resilient means coupling the plunger to said detonator, said resilient means yielding between the resistance to extrusion of the fluid and the impelling inertia movement of the detonator towards said switch when the detonator is engaged by said booster, the heavier-tensioned part of the last mentioned resilient means being of sufficient strength by reactive expansion after compression to fully drive said plunger and cause the operation of said switch by the extruded fluid then bridging the contacts.

JAMES W. CHANNELL.
